UNITED STATES PATENT OFFICE.

SILAS H. RANDALL, OF WYOMING, OHIO, ASSIGNOR OF ONE-HALF TO
JAMES D. RANDALL, OF SAME PLACE.

LEATHER-CREASING MACHINE.

SPECIFICATION forming part of Letters Patent No. 381,029, dated April 10, 1883.

Application filed December 20, 1887. Serial No. 258,452. (No model.)

To all whom it may concern:

Be it known that I, SILAS H. RANDALL, a citizen of the United States of America, residing at Wyoming, in the county of Hamilton 5 and State of Ohio, have invented certain new and useful Improvements in Leather-Creasing Machines, of which the following is a specification, reference being had therein to the accompanying drawings.

This invention relates to those leather-creasing machines which include two distinct trains 10 of rolls or revolving creases between which the strap or other piece of leather is run; and my improvement consists in providing such machines with a pair of idler gear-wheels that communicate motion from one train to the other and yet permit a proper shifting or adjustment of either of the trains, so as to admit thick or thin straps. These idler gear-wheels 15 can be very conveniently applied to the peculiar form of leather-creasing machine seen in Letters Patent No. 357,230, granted to me February 8, 1877, or they may be fitted to an ordinary creasing-machine, as hereinafter more fully described.

In the annexed drawings, Figure 1 is an end elevation of a leather-creasing machine embodying my improvements. Fig. 2 is a plan of said machine.

The end plate or standard, A, lower shaft, B, lower train of rolls, C, upper shaft, D, upper train of rolls, E, rock-shaft F, swinging arm G, and pin H, being the same in construction and operation as in my patent above referred to, require no further description in this specification. Rock-shaft F is pierced near its end to admit a spring-pin, f, that retains a washer, I, against the face of a master idler-wheel, J, which wheel revolves freely 30 around said shaft. This master-idler gears with an idler-pinion, K, journaled on a stud-shaft, L, that projects horizontally from the standard A. l is a spring-pin that prevents the pinion slipping off the shaft. Idler-pinion K engages with a gear-wheel, M, keyed to the lower shaft, B, which shaft has a square arbor, b, to which the crank N is applied. The upper shaft, D, has a gear-wheel, O, keyed to it, which wheel engages with the master-idler J.

From the above description it is apparent that by properly turning the crank N the gear-wheel M, idler-pinion K, master-idler J, and gear-wheel O will revolve in the direction

of the arrows seen in Fig. 1, and thereby turn 55 the train of rolls C E in such a manner as to draw the strap in and crease it in the usual manner.

It is also apparent that when the front end 60 of arm G is raised to elevate the shaft D preparatory to admitting a thick strap between the rolls the wheel O will still remain in gear with the master-idler J, and thus insure the proper action of the creasers when the crank is turned. Furthermore, it is evident that 65 when this arm is swung up to the position indicated by the dotted line G' the gear-wheel of the upper rolls will still engage with the master-idler J, as shown by the dotted circle O'.

It will thus be seen that the upper train of 70 rolls is always in a position to be driven by the lower train, no matter how far apart said rolls may be set. In the drawings the master-idler J is represented as being considerably 75 larger than the other idler-wheel, K, which arrangement is due to the peculiar construction of machine illustrated; but in some cases these wheels may change position or be otherwise disposed to suit circumstances, or the improvement may be applied to a creasing-machine in 80 which the lower roll is swung instead of the upper, also, although not so advantageously, to machines in which the moved roll, whether 85 upper or lower, is moved in a straight line instead of an arc. Finally, it is to be understood that the swinging arm G is duplicated at the other end of the machine, but the idler-wheels need be applied only to one end of the rolls.

I claim as my invention—
The combination, in the herein-described 90 leather-creasing machine, of an unadjustable creasing-roll having a gear-wheel at one end, an adjustable creasing-roll having a gear-wheel at one end, a rock-shaft arranged longitudinally of the machine, a swinging arm rigidly secured to each end of said rock-shaft, which arms carry the adjustable creasing-roll, and a pair of idler-wheels that communicate motion 95 from one roll-gear to the other, one of said idler-wheels being journaled upon said rock-shaft, for the purpose set forth.

In testimony whereof I affix my signature in presence of two witnesses.

SILAS H. RANDALL.

Witnesses:

JAMES H. LAYMAN,
SAM'L. S. CARPENTER.
